(57) **CLAIM**

The ornamental design for a file tab, as shown and described.

DESCRIPTION

FIG. 1 is a front view of the file tab.

FIG. 2 is a back view thereof.

FIG. 3 is a front folded view of FIG. 1 folded along a fold line.

FIG. 4 is the back folded view of FIG. 1 folded along a fold line.

FIG. 5 is a partially folded perspective view thereof; and, FIG. 6 is a perspective view of the design folded and attached to a hanging folder. The hanging folder forms no part of the claim, but is only shown for environment.

The features shown in broken lines depict environmental subject matter only and form no part of the claimed design. The file tab has no appreciable thickness and the side views are therefore not shown.

1 Claim, 6 Drawing Sheets
